TILTING LADLE

Louis A. Camerota, Burlington, N. J., assignor to
 Florence Pipe Foundry & Machine Company,
 Florence, N. J., a corporation of New Jersey

Application July 20, 1935, Serial No. 32,321

4 Claims. (Cl. 22—83)

This invention relates to tilting ladles and is particularly applicable to ladles of the type used to charge molds on a centrifugal casting machine.

Difficulties have heretofore been experienced with tilting ladles due to the tendency for slag or other impurities in the metal to rise to the top of the ladle, and in order to prevent such matter from being carried over into the mold, it has been customary to skim the surface of the metal and thus to remove the impurities before the ladle is discharged by tilting. Moreover, the provision of a skimming device near the mouth of a ladle renders it difficult to maintain a uniform or even flow of metal from the ladle to the pouring spout, it being important that the contents of the ladle shall flow smoothly over the pouring lip without surging or splashing.

Accordingly, the principal object of the present invention is to provide a skimming device which satisfactorily skims the metal in its passage through the mouth of the ladle, and at the same time to form the mouth of the ladle in relation to the pouring spout in such manner that the metal will flow evenly, without surging or splashing, as the ladle is tilted to discharge its contents.

A more specific object of the invention is to provide a skimming device which is maintained out of contact with the metal content of the ladle except when the ladle is tilted, and which is adapted to be moved from an operative position at the mouth of the ladle to a position clear of the top thereof where it is readily accessible for cleaning.

Other objects and advantages characterizing my invention will become more fully apparent from the description hereinafter set forth of one example or embodiment thereof, having reference to the accompanying drawings. Of the drawings:

Fig. I represents a side elevation of a tilting ladle in its normal or upright position, a carriage for supporting the same, and a pouring ladle for conveying the metal to a rotary mold.

Fig. II represents a plan view of the same.

Fig. III represents a side elevation similar to Fig. I, with parts shown in section to better disclose important features of the tilting ladle; and

Fig. IV represents a fragmentary cross section of the ladle and pouring spout, taken as indicated by the lines IV—IV in Fig. II, showing the ladle in the position which it occupies when tilted.

With particular reference to Fig. I of the drawings, there is shown a pouring assembly comprising generally a tiltable ladle 1, a ladle carry-

ing bracket 2 pivoted on spaced frame members 3, and a pouring spout 4. The ladle is equipped at the mouth thereof with a skimming device which is comprehensively designated at 6.

While the particular means of mounting the ladle 1 for tilting movement about the frame members 3 may be varied to a considerable extent, I have selected for illustration a mounting of the type described in my pending application for U. S. Letters Patent, Serial No. 32,322, filed July 20, 1935. In this arrangement the ladle carrying bracket 2 is provided with trunnions 7 at the top thereof which engage bearings 8 within the frame members 3. A pair of arms 9 carrying the trunnions 7 are cross connected by a plate 10. On the ladle 1 there are hook shaped gussets 11 engaging the top edge of the transverse plate 10 of the ladle carrying bracket 2. For attaching the ladle 1 firmly to the ladle carrying bracket 2, there is also provided a pair of hook shaped projections 12 on the bottom ends of the arms 9 which engage laterally extending pins 13 at the base of the ladle. The ladle is thus held by its own weight upon the ladle carrying bracket 2, but is readily removable by raising it in a vertical direction which may be accomplished by applying lifting tackle to a bail 14 attached to the top of the ladle.

The pouring spout 4 has at its upper end a pair of laterally extending pins 15 which are engaged by hook-shaped adjustable brackets 16 mounted on the frame members 3. Similarly at its lower end the pouring spout 4 has a pair of depending lugs 17 adapted to rest upon a bar 18a carried by a pair of adjustable brackets 18. The brackets 16, 18 are slotted and secured to the frame members 3 by bolts or the like, and in this manner the brackets are rendered vertically adjustable so that the end of the pouring spout may be positioned in the desired relation to the pouring lip 19 of the ladle 1.

As most clearly shown in Figs. III and IV, the ladle 1 of this invention has a forward inclined wall 20 and a rear wall 21 which is substantially arcuate in cross section. At the mouth of the ladle the inclined wall 20 terminates in a pouring lip 19 of special formation. It will be particularly noted that the forward edge 22 of the lip 19 is substantially coincident with the axis of the trunnions 7 about which the ladle 1 is tilted, and accordingly the trough of the pouring spout 4 is substantially tangent to the upper curved surface of the lip 19 when the ladle begins to discharge its content. Immediately in the rear of the curved portion of the lip 19 there is provided

a shoulder 24 which serves as a dam or weir, and which in connection with the skimming device hereinafter described serves to trap impurities in the metal.

The skimming device 6 comprises a blade in the form of a flat plate 25 secured to a pair of angle pieces 26 which are in turn affixed to a shaft 27 extending transversely across the mouth of the ladle 1. Attached to the shaft 27 at one side of the ladle there is a handle 28, and at the other side of the ladle there are arms 29, 30, shown most clearly in Fig. I, which alternately engage a laterally projecting pin 31, and thus serve as stops. When the arm 29 engages the pin 31, the blade 25 is maintained in a position within the mouth of the ladle with its bottom edge extending downwardly to a predetermined distance above the surface over which the metal is poured and at a predetermined distance in the rear of the shoulder 24. When the handle 28 is manipulated to swing the skimming device to a reverse position, as indicated in broken lines in Fig. IV, the arm 30 engages the pin 31 and the skimming device is maintained outside the ladle in a position where it is accessible for cleaning.

In the illustrated example of my invention, the tiltable ladle 1 is mounted on a movable carriage 34 having wheels 35 engaging parallel rails 36. The carriage 34 is adapted to be progressed back and forth on the rails 36 by means of a fluid operated cylinder 37, and in this manner the free end of the pouring spout 4 (not shown) is brought to a position within the end of the rotary mold of the centrifugal casting machine. Elevation and depression of the ladle 1 is accomplished by means of an additional fluid operated cylinder 38 pivoted at 39 on the carriage 34. The plunger 40 associated with the cylinder 38 is pivotally attached at 41 to the ladle carrying bracket 2. Certain of the pipe connections through which the pressure medium flows, including a control valve 42, are indicated comprehensively at 43. The details of the mechanism for moving the carriage 34 and for tilting the ladle 1, as well as the apparatus employed for controlling such movements, are not material to the present invention, and description thereof is here omitted. Such mechanism is fully described, however, in my pending application for U. S. Letters Patent, referred to above, which is specifically directed to such a form of ladle carriage and operating mechanism for progressing the carriage and tilting the ladle.

With reference particularly to Fig. IV, it will be apparent that the mouth of the ladle 1 is specially formed to effect a uniform and smooth flow of metal from the ladle to the pouring spout 4, without surging or splashing. The curved portion of the lip 19 affords a ridge which, together with the bottom edge of the blade 25 positioned in the rear thereof, traps the flow of metal, and causes impurities to collect at the rear of said ridge and not to be carried over through the mouth of the ladle and the trough of the pouring spout. Not only is the surface of the metal skimmed by engagement with the blade 25, but

the flow is controlled, so that the stream does not splash or surge but passes smoothly over the lip of the ladle and from thence to the connecting spout 4. The positioning of the forward edge 22 of the lip of the ladle substantially coincident with the tilting axis, makes it possible to provide a very short gap between the mouth of the ladle and the end of the pouring spout so that the spout forms substantially a continuation of the pouring lip, and there is no appreciable drop in the flow of metal over the curved portion of the lip.

While I have described my invention in some detail, and have disclosed a particular form of mounting for a tilting ladle including a movable carriage, it will be apparent that the invention herein is directed particularly to the novel formation at the mouth of the ladle and the skimming device associated therewith, and numerous changes may be made in the form of the apparatus herein disclosed without departing from the spirit of the invention as defined in the annexed claims.

Having thus described my invention, I claim:

1. In combination with a pivotally mounted ladle of the character described, having a lip at the mouth thereof with its forward edge substantially coincident with the axis about which the ladle is pivoted for tilting, and having a dam formed immediately in the rear of said lip, a skimming device having a blade maintained at a predetermined operative position immediately in the rear of said dam and adapted to skim the surface of the metal and to trap its impurities at said dam, said lip and dam merging with a smooth curve thereby to prevent surging or splashing of the metal as it is discharged through the mouth of the ladle.

2. In combination with a pivotally mounted ladle of the character described, having a lip at the mouth thereof smoothly curved and merging with a dam formed immediately in the rear of said lip, a skimming device having a blade movable from a predetermined operative position within the mouth of the ladle and in the rear of said dam, where it is adapted to skim the surface of the metal and to trap its impurities behind said dam incident to discharge of the metal through the mouth of the ladle, to a position beyond the mouth of the ladle and to one side of the area overlying its metal content when at rest.

3. Apparatus in accordance with claim 1 further characterized by a handle for swinging the blade of the skimming device from a position at the mouth of the ladle to a position outside the ladle and to one side of the area overlying its metal content when at rest, and means limiting the swinging movement of said handle.

4. Apparatus in accordance with claim 1 further characterized by a handle for swinging the blade of the skimming device from a position at the mouth of the ladle to a reverse position wherein the skimming edge of the blade extends upwardly outside the mouth of the ladle.

LOUIS A. CAMEROTA.
